CLAIM

The ornamental design for a dual foot magnetic pulse therapy device, as shown and described.

DESCRIPTION

FIG. 1 is a perspective view of the distal end of the dual foot magnetic pulse therapy device;

FIG. 2 is a back perspective view thereof;

FIG. 3 is an front view thereof;

FIG. 4 is a back view thereof;

FIG. 5 is a right view thereof;

FIG. 6 is a top view thereof;

FIG. 7 is a cross-sectional view of FIG. 6 thereof; and,

FIG. 8 is a cross-sectional view of FIG. 2.

The dash-dot broken lines shown in Figures illustrate portions of the dual foot magnetic pulse therapy device that form no part of the claimed design.

The dash-dot lines in FIGS. 1 and 6 are for the purpose of depicting the cut line of the cross-section views and form no part of the claim.

1 Claim, 6 Drawing Sheets
